(57) **CLAIM**

The ornamental design for a telescopic stool as shown and described.

DESCRIPTION

FIG. 1 is a perspective view of a telescopic stool, showing my new design;

FIG. 2 is a front view thereof;

FIG. 3 is a rear view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings represent portions of the telescopic stool that form no part of the claimed design. The pattern of the solid black shading on the telescopic stool represents the color black.
